UNITED STATES PATENT OFFICE.

JAMES H. LA BATE, OF BROCKTON, MASSACHUSETTS.

THREAD CONTROLLING AND UNWINDING DEVICE FOR SEWING-MACHINES.

No. 849,140.

Specification of Letters Patent.

Patented April 2, 1907.

Application filed December 21, 1906. Serial No. 348,890.

To all whom it may concern:

Be it known that I, JAMES H. LA BATE, of Brockton, in the county of Plymouth and State of Massachusetts, have invented certain new and useful Improvements in Thread Controlling and Unwinding Devices for Sewing-Machines, of which the following is a specification.

This invention has for its object to provide means for supporting a spool of thread on the arm of a sewing-machine for guiding the thread from the spool to the head and tension devices of the machine in such manner as to insure a free and regular delivery of the thread and to prevent the possibility of coils or loops of the thread dropping over the end or ends of the spool and becoming entangled with the spool and its support.

The invention consists in the improvement which I will now proceed to describe and claim.

Of the accompanying drawings, forming a part of this specification, Figure 1 represents a side elevation showing the arm of a sewing-machine with my improved unwinding device applied thereto. Fig. 2 represents a front elevation showing the unwinding device removed from the sewing-machine arm.

The same letters of reference indicate the same parts in all the figures.

In the drawings, *a* represents the arm of a sewing-machine.

b represents a vertical stud or spindle affixed to the arm and projecting upwardly therefrom.

c represents a head or block detachably secured to the stud *b*, the block being preferably provided with an aperture adapted to receive the stud and with a set-screw *e*, adapted to detachably secure the block to the stud.

f represents a bent rod, one end of which is affixed to the block *c*, the rod rising from the block and being bent at a point above the same to form a horizontal arm or spindle *f'*, adapted to pass through the bore of the spool *g*, the spool being therefore horizontally supported and adapted to rotate on a horizontal axis formed by the spindle *f'*. The spindle is provided with suitable stops *h h* to confine the spool against loose endwise movement, said stops being preferably collars detachably secured by set-screws or otherwise to the spindle.

i represents a bent rod affixed at one end to the block *c* by means of a set-screw *j* or otherwise, the rod extending vertically up-

ward from said block and being bent at a point above the block and above the spindle *f'* to form a horizontal arm *i'*, located over the spindle *f'*. To said arm is affixed a thread-guide *j*, consisting of a finger suitably affixed, detachably or otherwise, to the arm *i'* and projecting downwardly therefrom, the said finger having an orifice *j'*, through which the thread *k* from the spool is adapted to pass. As shown in Fig. 2, the thread-guide *j* is directly over the longitudinal center of the spool, so that a stretch of the thread passing from either end of the spool is inclined inwardly from the adjacent end of the spool, as indicated by the dotted lines *m m* in Fig. 2.

The thread passes from the spool through the guide *j* and from thence to the usual or any suitable guide *n* on the sewing-machine head, the thread passing from the guide *n* to the needle and engaging the usual or any suitable tension devices on its way to the needle. As the thread unwinds it passes upward to the guide, the portions drawn from the ends of the spool being inclined inwardly toward the center of the spool, so that the thread never overhangs or projects outwardly over the ends of the spool, and consequently cannot become caught between the ends of the spool and the spindle on which the spool is supported.

I have here shown the device adapted to accommodate one spool; but it is obvious that the number of spool-holding spindles and thread-guides may be increased to accommodate any desired number of spools, each spindle having a corresponding thread-guide, the two relatively arranged, as here shown.

The stops *h h* are relatively adjustable to accommodate spools of different lengths, and one or both of said stops may be movable on the spindle *f'* and provided with holding means, such as a set-screw *h'*, for securing it at any desired adjustment, although, if desired, the inner stop may be fixed or immovable on the spindle, the outer stop being adjustable toward and from the inner stop. The thread-guide is correspondingly adjustable on the arm or holder *i'*, so that it may be centralized relatively to the stops *h h* whatever may be the relative positions of said stops, the thread-guide being provided with means, such as a set-screw *j'*, for securing it in any position to which it may be adjusted.

It will be observed that the device as a

whole comprises an attachment which is capable of being applied to or removed from the ordinary vertical spool-spindle, such as that shown at *b* in the drawings. In other words, instead of putting a spool on the vertical spindle *b*, as is the most customary method, the block or base *c* is applied to said spindle and secured there, said block or base having adjustably secured to it the spool-spindle and the thread-guide. By this construction the device as a whole can be removed from the sewing-machine without changing the relative positions of the spool-spindle and the thread-guide, thereby enabling the attachment to be reapplied to the spindle *b* expeditiously and without having to readjust the relative positions of the spool-support and overhead thread-guide.

I claim—

- 20 1. An unwinding device for sewing-machines, comprising a substantially horizontal spool-spindle having stops to prevent end-wise displacement of the spool, said stops being adjustable to conform to spools of different lengths, a thread-guide located above the spindle, and means for holding the thread-

guide in a plane between the vertical planes of the ends of the spool, said supporting means having provisions for laterally adjusting the thread-guide to correspond with adjustments of said stops to centralize it for spools of different lengths. 30

2. An unwinding device for sewing-machines, comprising two bent standards, each having a vertical supporting portion, and a horizontal portion extending laterally therefrom, one of said horizontal portions constituting a spool-spindle, and being provided with spool-stops, while the other horizontal portion constitutes a thread-guide holder, a base to which said standards are attached, said base having means for engagement with the frame of the machine, and a thread-guide affixed to the said holder, and located in a plane between the vertical planes of the ends 40 of the spool. 45

In testimony whereof I have affixed my signature in presence of two witnesses.

JAMES H. LA BATE.
